(57) **CLAIM**

The ornamental design for a cable securing apparatus, as shown and described.

DESCRIPTION

FIG. 1 illustrates a perspective view of the outside of a cable securing apparatus showing the new design;

FIG. 2 illustrates a perspective view of the inside thereof;

FIG. 3 illustrates a bottom perspective view in an alternative configuration thereof;

FIG. 4 illustrates a top perspective view in an alternative configuration thereof;

FIG. 5 illustrates a bottom perspective view in an alternative configuration view thereof;

FIG. 6 illustrates a top perspective view in an alternative configuration thereof;

FIG. 7 illustrates a top orthogonal view in an alternative configuration thereof;

FIG. 8 illustrates a bottom orthogonal view in an alternative configuration thereof; and

FIG. 9 illustrates a rear orthogonal view in an alternative configuration thereof;

FIG. 10 illustrates a front orthogonal view in an alternative configuration thereof;

FIG. 11 illustrates a right orthogonal view in an alternative configuration thereof;

FIG. 12 illustrates a left orthogonal view in an alternative configuration thereof; and,

FIG. 13 illustrates a right orthogonal view of the outside thereof.

The broken lines shown in the drawings are for the purpose of illustrating portions of the cable securing apparatus that form no part of the claimed design.

1 Claim, 7 Drawing Sheets
